UNITED STATES PATENT OFFICE.

FRANK R. GOODE, OF DECATUR, ILLINOIS, ASSIGNOR TO R. O. BURROUS
AND W. M. BREWER, OF PIERSON STATION, ILLINOIS.

DESIGN FOR A ROPE AND WIRE HOLDER.

SPECIFICATION forming part of Design No. 29,810, dated September 6, 1898.

Application filed June 20, 1898. Serial No. 684,014. Term of patent 7 years.

To all whom it may concern:

Be it known that I, FRANK R. GOODE, a citizen of the United States, residing at Decatur, in the county of Macon and State of Illinois, have invented and produced a new and original Design for a Rope and Wire Holder; and I do hereby declare the following to be a full, clear, and exact description of the same, reference being had to the accompanying drawings, forming a part thereof.

This invention relates to a new and original design for rope and wire holders. The same is embodied in the configuration hereinafter described, and shown in the accompanying drawings.

In the drawings, Figure 1 is an elevation of the holder, and Fig. 2 is an edge view.

The design consists in the peculiarly-shaped holder A, having a curved upper end B, terminating in two rearwardly-curved hooks or horns C. The lower contour of the portion A is gradually curved downward and has thereon an upwardly-curved branch or hook D, from the lower side of which is a downwardly and rearwardly curved hook or supplemental horn E. From the base of the hook D the portion A is curved and extends downward,

its lower end terminating in fingers e. Adjacent to the holder portion A is the base or post portion F, having projections at opposite ends.

The holder portion is secured to a bracket from the post portion, and the dividing-line between the holder and the post portion is conveniently curved in the lines of an ogee or compound curve, the space between the upper rear portion of the holder and the post being gradually increased.

The essential feature of the design may therefore be stated as consisting, primarily, in the peculiarly-shaped holder portion, comprising the rearwardly-extending horns and the hooks on the under side of the holder.

Having thus described the invention, what is claimed as new, and desired to be secured by Letters Patent, is—

The design for a rope and wire holder, substantially as shown and described.

In testimony whereof I affix my signature in presence of two witnesses.

FRANK R. GOODE.
